UNITED STATES PATENT OFFICE

167,540

DIVER TOY

Bayard C. Reed and Eoina Nudelman, Chicago, Ill.

Application May 17, 1950, Serial No. 10,001

Term of patent 14 years

(Cl. D34—15)

To all whom it may concern:

Be it known that we, Bayard C. Reed, a citizen of the United States, residing at Chicago, State of Illinois, and Eoina Nudelman, a citizen of the Republic of France, residing at Chicago, State of Illinois, have invented a new, original, and ornamental Design for a Diver Toy, of which the following is a specification, reference being had to the accompanying drawing, forming a part hereof.

Figure 1 is a side view of the diver toy showing our new design.

Figure 2 is an end view thereof.

Figure 3 is a top plan view thereof.

We claim:

The ornamental design for a diver toy, as shown.

BAYARD C. REED.
EOINA NUDELMAN.
